CLAIM

The ornamental design for a jar, as shown and described.

DESCRIPTION

FIG. 1 is a front perspective view of a jar with a lid showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a front perspective view of the jar without the lid showing my new design;

FIG. 9 is a top plan view thereof;

FIG. 10 is a bottom plan view thereof;

FIG. 11 is a front elevational view thereof;

FIG. 12 is a rear elevational view thereof;

FIG. 13 is a right side elevational view thereof;

FIG. 14 is a left side elevational view thereof; and,

FIG. 15 is an exploded view of the jar with the lid of FIG. 1. The lid is shown removed on FIGS. 8-14 for ease of illustration.
